UNITED STATES PATENT OFFICE.

WALTER J. HERSCHEDE, OF CINCINNATI, OHIO, ASSIGNOR TO THE HERSCHEDE HALL CLOCK COMPANY, OF CINCINNATI, OHIO, A CORPORATION OF OHIO.

DESIGN FOR A HALL CLOCK.

Application filed October 30, 1926. Serial No. 19,538. Term of patent 14 years.

To all whom it may concern:

Be it known that I, WALTER J. HERSCHEDE, a citizen of the United States of America, and a resident of Cincinnati, in the county of Hamilton and State of Ohio, have invented a new, original, and ornamental Design for a Hall Clock, of which the following is a specification, reference

being made to the accompanying drawing, forming part thereof.

The figure is a perspective view of a hall clock showing my new design.

I claim:

The ornamental design for a hall clock as shown.

WALTER J. HERSCHEDE.
